(57) **CLAIM**

The ornamental design for a handle, as shown and described.

DESCRIPTION

FIG. 1 is a front elevational view of a handle showing my new design;

FIG. 2 is a rear elevational view thereof;

FIG. 3 is a top plan view thereof;
FIG. 4 is a sectional view thereof, taken substantially along the line 4—4 of FIG. 1;

FIG. 5 is a left end view thereof; and,

FIG. 6 is a right end view thereof.

The bottom view thereof is identical to the top view.
